STEAM GENERATOR

Thomas B. Stillman, South Orange, N. J., assignor to The Babcock & Wilcox Company, Newark, N. J., a corporation of New Jersey

Application October 12, 1938, Serial No. 234,526

15 Claims. (Cl. 122—491)

The present invention relates to the construction and arrangement of internal baffle systems for a steam and water drum of a water tube steam boiler, and, more particularly, a steam boiler having a multiplicity of steam generating tubes discharging directly into the water space of the drum.

With the small diameter high capacity steam and water drums used in three drum express type marine boilers, for example, it has been found extremely difficult to carry a water level above the center line of the drum without danger of substantial moisture carryover in the outgoing steam. This is due to a tendency for the steam and water discharged from the tubes to flow up through the water locally and violently disturb the water surface. When such boilers are employed, the feed water supply to the boiler is ordinarily manually controlled by a water tender. Rapid and substantial fluctuations in the drum water level which occur when turbulent conditions are present in the water, render the water tending operations difficult.

In such boilers, various arrangements of submerged baffles have been suggested for reducing turbulence of the water in the steam and water drum by attempting to effect uniform liberation of the steam over the area of the water surface. One such baffle arrangement which has met with fair success is shown in the Donald Patent 1,884,614 as a submerged V-shaped perforated baffle in the path of discharge of the generating tubes having the highest rate of steam generation. With high water levels and increasing steaming capacities, the Donald arrangement has been found to be inadequate to maintain a substantially dry steam discharge and steady water level conditions.

The main object of my invention is the provision of an improved construction and arrangement of a submerged baffle system for a steam and water drum of a steam boiler of the character described, the operation of which is characterized by the maintenance of a substantially dry steam discharge and steady water levels in the drum under high capacity operation, even with high water levels in the drum.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have

illustrated and described preferred embodiments of my invention.

Of the drawings:

Fig. 1 is a sectional elevation of a three drum express type marine boiler having a steam and water drum baffle system constructed in accordance with my invention;

Fig. 2 is an enlarged view of the steam and water drum of Fig. 1;

Fig. 3 is an enlarged view of the feed pipe shown in Fig. 2;

Fig. 4 is an enlarged view of the dry pipe shown in Fig. 2;

Fig. 5 is a horizontal section taken on the line 5—5 of Fig. 2;

Fig. 6 is a vertical section taken on the line 6—6 of Fig. 2;

Fig. 7 is a plan view of the V-shaped baffle taken on the line 7—7 of Fig. 2;

Fig. 8 is a view similar to Fig. 2 illustrating a modified construction; and

Figs. 9 and 10 are full size sectional views taken on the lines 9—9 and 10—10 respectively of Fig. 8.

While my invention is applicable to various types of steam boilers having a submerged connection of the steam generating tubes into a steam and water drum, it is particularly designed for and especially useful in three drum express type marine boilers, such as shown in Fig. 1. The steam boiler illustrated has a horizontally arranged steam and water drum 10 connected to a pair of laterally offset parallel lower water drums 11 and 12 by oppositely inclined banks of water tubes 13 and 14 respectively. The inverted V-shaped chamber therebetween is divided by a vertical partition 15 into separate furnaces 16 and 17. The partition includes a row of water tubes 18 connected to the drums 10 and 11. The tube bank 13 is divided into a pair of spaced tube groups and the space therebetween utilized for the installation of a steam superheater 19. Each furnace is heated by a separate group of fuel burners, diagrammatically indicated at 20, in one of its end walls and the heating gases after traversing the corresponding tube bank pass across an extended surface economizer 21 to the stack. With this construction, only the furnace 17 is used in starting-up and the furnace 16 operated when there is an adequate flow of steam through the superheater. Control of the firing or combustion in the furnace 16 is used to regulate superheat temperatures, and that in furnace 17 to regulate the generation of steam.

As shown in Figs. 2 and 3, feed water is supplied to the steam and water drum through a sub-

merged feed pipe 25 entering through one end of the drum and capped at its other end. Holes 26 along the upper side of the feed pipe provide a distribution of the feed water along the length 5 of the drum. A dry pipe 27 extends along adjacent the top of the drum with holes 28 in its upper side for the passage of steam. The dry pipe is connected to a central steam outlet 29 and a safety valve connection 30.

10 In the boiler described, the designed water level in the steam and water drum is at the horizontal center line of the drum. As shown in Figs. 1 and 2, all of the tubes in the tube banks 13 and 14 enter the drum below this level.

15 With furnaces 16 and 17 in operation, most of the steam will be generated in the portions of the tube banks nearest the furnaces and the tubes in the outer portions of the tube banks will serve as downcomers, supplemented by groups of down-20 comers 31 at the ends of the tube banks. The submerged discharge of a multiplicity of high velocity streams of steam and water upward through the water along the longitudinal central part of the drum tends to effect a highly turbulent condition in the water space of the drum with a high exit velocity of the steam leaving the water space mainly above the tubes nearest the furnace. Such conditions contribute to entrainment of water by the steam leaving the water space and 25 the production of wet steam with a relatively high solid content. With the drum baffle system of my invention, a substantially uniform liberation of steam at a reduced water exit velocity across the entire water surface is effected.

30 My improved drum baffle system is divided as shown in Fig. 1, into three parts, a lower V-shaped baffle 40, a pair of wing baffles 50, and a horizontal center baffle 60. The V-shaped baffle 40 is formed by two oppositely inclined perforated steel plates 41 having upturned flanged inner edges 42 connected together along the vertical center line of the drum. The baffle plates 41 are supported at an acute angle to the horizontal, approximately 20°, superjacent the feed pipe 25. The V-baffle 45 is supported by correspondingly bent plates 43 carried by the feed pipe, which in turn is supported at longitudinally spaced points by recessed bars 44 suspended from angle members 45 by hanger bolts 46. The angle members 45 extend 50 across the drum at about its water line and are carried by bent plates 47 welded to the drum wall. The hanger bolts 46 are surrounded by spacer sleeves 48 and extend downwardly through the baffle plates 41 to hold the feed pipe and thereby 55 the V-baffle fixed in position with the apex of the baffle approximately half way down below the designed water level.

Each of the wing baffles 50 is formed by perforated steel plates 51 connected to one side wall 60 of the drum at the designed water level and sloping downwardly to a point below the water level and in approximate vertical alignment with the corresponding outer edge of the V-baffle. The baffle plates 51 have flanged edge portions to permit 65 their connection to one another and to the supporting angle members 45. The wing baffles terminate short of the full length of the V-baffle and spaces therebeneath are closed at their ends by perforated vertical angle plates 52. The plates 70 52 partly surround the upper ends of the down-comers 31 and function to separate steam from the water in the drum flowing to the down-comers 31.

The horizontal center baffle 60 is formed by 75 perforated flat steel plate sections 61 having up-

turned flanged edge portions connected to adjacent plates and to the angle members 45 and inner edge portions of the wing baffles 50. The center baffle is arranged below the designed water level, slightly below the inner edges of the wing baffles, and extends slightly beyond the ends of the V-baffle. The hanger bolts 46 and sleeves 48 extend through the corresponding plate sections 61. The sides of the space below the center baffle beyond the ends of the wing baffles are closed by perforated bent sections of the end plates 52.

The perforations in the baffle plates 41, 51, 52 and 61 illustrated are formed by holes $\frac{1}{4}$ " in diameter staggered throughout the plate area and totaling about 25% of the plate area.

Surface blow-off operations can be effected through a horizontally arranged perforated blow-off pipe 70 extending longitudinally of the drum just above the center baffle 60. The pipe 70 is supported from the angle members 45 by U-
bolts 71.

The drum baffle system described has been found to be highly effective for its intended purposes. In one test installation having 4360 sq. ft. of boiler heating surface and a drum pressure of 600 lbs. per sq. in., it was found that when generating 154,596 lbs. of steam per hr. (143% rated capacity) corresponding to 54.5 cu. ft. of steam per minute per sq. ft. of drum water surface, the moisture in the outgoing steam was less than $\frac{1}{4}$ of 1%. Under full power conditions it was found possible to carry a water level within $1\frac{1}{2}$ " from the top of the gauge glass with less than 0.6 of 1% moisture in the delivered steam.

In operation, the high velocity streams of steam and water entering the drum impinge upon the feed pipe 25 and V-baffle 40 which causes them to be dispersed throughout the width of the drum. Some of the streams are deflected towards the sides of the drum by the inclined arrangement of the V-baffle plates and these streams are obstructed and broken up by the wing baffles 50 before leaving the water space. In view of the low location of the V-baffle and the high velocity steam discharge, some of the streams will pass through the V-baffle perforations at a high velocity and these streams are later obstructed and dispersed by the center baffle. The various submerged baffles thus cooperate to provide a substantially uniform flow of steam from all of the liberating surface of the drum above the connected tubes in spite of its relatively localized admission to the bottom of the drum. At the same time the larger steam bubbles are broken up and the water separated from the steam.

In Figs. 8-10 is illustrated a modified baffle construction also particularly adapted for use in steam boilers of the type described. In the modified construction, the amount of perforated baffle area in the drum 10 is substantially increased and arranged as hereinafter described. The perforated baffle area of the lower V-shaped baffle 40 is increased by the addition of perforated plates 80 and 81 below and above respectively each section thereof. While the plates 41 are constructed with $\frac{1}{4}$ " diameter perforations totaling about 25% of the plate area, it has been found desirable to make the plates 80 and 81 with perforations $\frac{1}{8}$ " in diameter and totaling about 20% of the plate area. The plates 80 are made flat throughout their extent and arranged in contact with the underside of the plates 41 to reduce the effective flow area through the plates 41. The plates 81 have their edge portions similarly bent to form a shallow dish-shaped structure and arranged with

their bent edge portions in contact with the corresponding plate 41. The perforated body of each plate 81 is held in the spaced relation with the plate 41 described and the plates 40, 80 and 81 held assembled by any suitable means, such as the bolts 82. Perforated plates 90 similar in construction to the plates 81 are arranged at opposite sides of each wing baffle plate 51 and each center baffle plate 61. The modified baffle construction described has been found to result in a lower moisture content of the steam delivered under similar boiler load and water level conditions than the baffle construction shown in Figs. 1-7, even with a high solid concentration in the boiler water.

15 While in accordance with the provisions of the statutes I have illustrated and described herein the best forms of the invention now known to me, those skilled in the art will understand that changes may be made in the form of the apparatus disclosed without departing from the spirit of the invention covered by my claims, and that certain features of my invention may sometimes be used to advantage without a corresponding use of other features.

25 This application is a continuation in part of my prior application Serial No. 169,080, filed Oct. 15, 1937.

I claim:

1. In a vapor generator, a liquid and vapor drum having vapor generating tubes connected to the lower part thereof, a submerged V-shaped perforated baffle extending in an upright position across the path of discharge from said vapor generating tubes and having its side edges spaced from the corresponding sides of said drum, and a horizontally arranged baffle structure extending across said drum above said V-baffle and comprising a plurality of vertically spaced perforated baffles, the total flow area through the uppermost baffle being 40 less than the total flow area through the subjacent baffle.

2. In a vapor generator, a horizontally arranged liquid and vapor drum having vapor generating tubes connected to the lower part thereof at opposite sides of the vertical axial plane of said drum, a submerged V-shaped perforated plate baffle extending in an upright position across the path of discharge from said vapor generating tubes and having its side edges spaced from the corresponding sides of said drum, and a horizontally arranged baffle structure extending across said drum above said V-baffle and comprising a plurality of normally submerged vertically spaced perforated plates, the total flow area through the uppermost 55 plate being less than the total flow area through the subjacent plate.

3. In a steam generator, a horizontally arranged steam and water drum having steam generating tubes connected to the lower part thereof, a submerged V-shaped perforated baffle extending in an upright position across the path of discharge from said steam generating tubes and having its side edges spaced from the corresponding sides of said drum, a pair of wing baffles above and extending across the spaces between said V-baffle and drum wall, and a horizontally arranged baffle extending across said drum above said V-baffle.

4. In a steam generator, a horizontally arranged steam and water drum having steam generating tubes connected to the lower part thereof, a submerged V-shaped perforated baffle extending in an upright position across the path of discharge from said steam generating tubes and having its side edges spaced from the corresponding sides of said drum, a pair of submerged perforated wing baffles

above and extending across the spaces between said V-baffle and drum wall, and a horizontally arranged submerged perforated baffle extending across said drum above said V-baffle and between said wing baffles.

5. In a steam generator, a horizontally arranged steam and water drum having steam generating tubes connected to the lower part thereof, a submerged V-shaped perforated baffle extending in an upright position across the path of discharge from said steam generating tubes and having its side edges spaced from the corresponding sides of said drum, a pair of submerged perforated wing baffles above and extending across the spaces between said V-baffle and drum wall, perforated end plates closing said spaces adjacent the ends of said drum, and a horizontally arranged submerged perforated baffle extending across said drum above said V-baffle and between and supported from said wing baffles.

6. In a steam generator, a horizontally arranged steam and water drum having steam generating tubes connected to the lower part thereof, a submerged shallow V-shaped perforated baffle extending in an upright position across the path of discharge from said steam generating tubes and having its side edges spaced from the corresponding sides of said drum, a pair of oppositely inclined submerged perforated wing baffles above and extending across the spaces between said V-baffle and drum wall, and a horizontally arranged submerged perforated sectional baffle extending across said drum above said V-baffle and between said wing baffles.

7. In a steam generator, a horizontally arranged steam and water drum having steam generating tubes connected to the lower part thereof, a submerged V-shaped perforated baffle extending across the path of discharge from said steam generating tubes and having its side edges spaced from the corresponding sides of said drum, a feed pipe extending longitudinally of said drum below said V-baffle, and means for supporting said V-baffle from said feed pipe.

8. In a steam generator, a horizontally arranged steam and water drum having steam generating tubes connected to the lower part thereof, a submerged V-shaped perforated baffle extending across the path of discharge from said steam generating tubes and having its side edges spaced from the corresponding sides of said drum, a feed pipe extending longitudinally of said drum below said V-baffle, means for supporting said V-baffle from said feed pipe, supporting members extending across said drum above said V-baffle, and means for supporting said feed pipe from said supporting members.

9. In a steam generator, a horizontally arranged steam and water drum having steam generating tubes connected to the lower part thereof at opposite sides of the vertical axial plane of said drum, a submerged V-shaped perforated baffle extending across the path of discharge from said steam generating tubes and having its side edges spaced from the corresponding sides of said drum, a feed pipe extending longitudinally of said drum below said V-baffle, means for supporting said V-baffle from said feed pipe, and means for supporting said feed pipe including supporting members extending across said drum above said V-baffle, cross-bars receiving said feed pipe, and hanger bolts extending from said supporting members through said V-baffle to said cross-bars.

10. In a vapor generator having a liquid and vapor drum and vapor generating tubes connected

- to the lower part thereof, a submerged V-shaped baffle extending in an upright position across the path of discharge from said vapor generating tubes and having its side edges spaced from the corresponding sides of said drum, and a horizontally arranged submerged baffle extending across said drum above said V-baffle, each of said baffles comprising a plurality of superposed perforated plates of different total flow areas.
10. 11. In a vapor generator having a horizontally arranged liquid and vapor drum and vapor generating tubes connected to the lower part thereof at opposite sides of the vertical axial plane of said drum, a submerged V-shaped baffle extending in an upright position across the path of discharge from said vapor generating tubes and having its side edges spaced from the corresponding sides of said drum, and a horizontally arranged submerged baffle extending entirely across said drum above said V-baffle, each of said baffles comprising a plurality of superposed perforated plates with the perforations in adjacent plates of substantially different size.
12. In a steam generator having a horizontally arranged steam and water drum and steam generating tubes connected to the lower part thereof, a submerged V-shaped baffle extending in an upright position across the path of discharge from said steam generating tubes and having its side edges spaced from the corresponding sides of said drum, a pair of submerged wing baffles above and extending across the spaces between said V-baffle and drum wall, a horizontally arranged submerged central baffle extending across said drum above said V-baffle and between and supported from said wing baffles, and each of said baffles comprising a plurality of superposed vertically spaced perforated plates with the perfora-
- tions in adjacent plates of substantially different size and substantially the same total flow area.
13. In a steam generator having a horizontally arranged steam and water drum and steam generating tubes connected to the lower part thereof, a submerged V-shaped baffle extending in an upright position across the path of discharge from said steam generating tubes and having its side edges spaced from the corresponding sides of said drum, and a pair of submerged wing baffles above and extending across the spaces between said V-baffle and drum wall, each of said wing baffles comprising a plurality of superposed vertically spaced perforated plates.
14. In a steam generator having a horizontally arranged steam and water drum and steam generating tubes connected to the lower part thereof, a submerged V-shaped baffle extending in an upright position across the path of discharge from said steam generating tubes and having its side edges spaced from the corresponding sides of said drum, said baffle comprising a plurality of superposed perforated plates with the perforations in adjacent plates of substantially different size.
15. In a steam generator having a horizontally arranged steam and water drum and steam generating tubes connected to the lower part thereof, a submerged shallow V-shaped perforated baffle extending in an upright position across the path of discharge from said steam generating tubes and having its side edges spaced from the corresponding sides of said drum, said baffle comprising an intermediate perforated plate and a pair of perforated baffle members at the upper and lower sides of said plate, said upper baffle member being arranged in spaced relation and said lower baffle member in contact with said intermediate plate.

THOMAS B. STILLMAN.
